UNITED STATES PATENT OFFICE.

GEOIGE W. CURRY, OF ST. LOUIS, MISSOURI.

FASTENER FOR THE MEETING-RAILS OF SASHES.

SPECIFICATION forming part of Letters Patent No. 291,608, dated January 1, 1884.

Application filed January 29, 1883. (Modol.)

To all whom it may concern:

Be it known that I, GEORGE W. CURRY, a citizen of the United States, residing at St. Louis and State of Missouri, have invented a new and useful Improved Sash-Lock, of which

5 the following is a specification.

My invention relates to improvements in sash-locks; and the objects of my improvements are, first, to provide an automatic or 10 self-closing sash-lock; secondly, to afford a safe, secure, and reliable burglar-proof sash-lock which can be easily applied to all window-sashes, will prevent their sagging, rattling, &c., and which will otherwise possess advantages of simplicity, strength, and durability 15 in construction, reliability in operation, and convenience for proper handling of the sashes. I attain these objects by the mechanism illustrated in the accompanying drawings, in

20 which—

Figure 1 is a plan view, showing my improved sash-lock applied to the window-sashes, and in locked condition. Fig. 2 is the same view of the lock, but in its "open" or unlocked condition, hence showing the thumb-lever and sliding bolt as withdrawn from their catches preparatory to raising or opening the sashes. Fig. 3 is a bottom plan of the sash-lock to better show its interior mechanism as 30 the parts appear when the lock is closed. Fig. 4 is a similar view of the under side or bottom of the sash-lock, representing the same internal operating parts when in open position. Fig. 5 is an edge view of the lock to show the 35 thumb-lever in its locked position, not only by its lug with the top face of the socket plate or catch, but having its arm at the same time in engagement with the mortise under the bevel-face of the catch. Fig. 6 is a face view 40 or elevation of the socket plate or catch, which is the only portion of the sash-lock that is fastened, and remains part of the face of the outer sash. Fig. 7 is an edge view of the lock-casing, with its bolt-opening, and edge view of the 45 arm of the thumb-lever, having a lug on its under face. Fig. 8 is a central sectional elevation on line 8 8 through the entire sash-lock when in locked condition. Fig. 9 is a bottom plan of the swinging or thumb lever. Fig. 10 represents both faces of the sashes to 50 which the lock is applied, the inner sash having an offset or portion cut away.

Similar letters refer to similar parts throughout the several views.

I will first describe that portion of the sash-lock that is applied to and remains part of the inside sash.

A represents the casing to contain the operating parts. The outer wall, A', of the casing, has the opening a, through which the bolt 60 passes, and at a' the casing has a shoulder above the line of the top face of the casing. (See Figs. 7, 8.)

b represents the spindle passing through the casing A, and fitted to partially turn in same. (See Figs. 3, 4, 8.)

My sliding bolt consists of the tongue or bolt c, proper, projecting from a bearing-plate, c', that has the mortise or slot c'', as clearly shown in Figs. 1, 2, 4, 8.

The spindle passes through the slot in the bearing-plate c'; hence the latter can be fitted to slide in the top of the casing A, the slot c'' freely permitting the said bearing-plate and its bolt to be moved backward and forward 75 for purposes of locking and unlocking the sash-lock.

I have provided the following automatic-acting parts to actuate the sliding bolt to enter and be locked in engagement with the 80 catch on the outer sash, or be unlocked, as the case may require.

D is an arm secured to and turning with the lower end of the spindle. The outer end of the arm D is pivoted to a connecting-arm, D', 85 which in turn has its outer end pivoted to the shank of the bolt c. (See Figs. 3, 4.) Hence, by partially turning the spindle, the arms D D' can be moved to draw the bolt c inward, and when completely drawn inward, so as to clear 90 the catch on the outer sash, the parts are in the open or unlocked condition shown in Figs. 2, 4.

To automatically close or lock the bolt parts, I simply provide the spring E, having one end 95 bearing against the spindle-arm D, the other end of the spring being fastened to the casing at e, as shown in Figs. 3, 4. As soon as the spindle is released the spring restores the bolt and its parts to a locked condition. Consequently the arms D D' and bearing-plate are also in original position. (See Fig. 3.) e' is a stop to limit the movement of the arm D to its proper place. (See Figs. 3, 4.)

F is the thumb-lever, by means whereof the operator slides back the bolt or opens the sash-lock. This thumb-lever has the central socket, f , the downward-projecting arm f' , and the lateral arm f'' , as shown in Figs. 1, 2, 5, 8, 9. By its sockets f the thumb-lever is keyed to the top of the spindle to operate the latter. By its projecting or lateral arm f'' the locking of the thumb-lever with the mortise 10 of the catch on the outer sash is effected, for purposes hereinafter stated. Further, the arm f'' has the lug f^3 to engage the shoulder of the catch on the outer sash, for purposes as will hereinafter appear.

15 The above-described parts constitute that portion of the sash-lock that is secured to the inside window-sash. The remaining portion of the sash-lock is secured to the outer sash, and consists simply of the catch G. This 20 catch G consists, in its entirety, of a single casting, of the constructive shape shown in Figs. 1, 5, 6, 8, and has the specific features, viz: the bevel-face at g , the mortise at g' , the shoulder at g'' , the socket g^3 , all as shown. It 25 is against the bevel-face g that the arm f'' of the thumb-lever strikes against in the act of lowering the inside sash, the said bevel-face causing the thumb-lever, as it descends, to be thrust or turned to one side, as will herein- 30 after appear. In the mortise g' the arm f'' of the lever enters to lock the sash-lock parts at said-named place. The shoulder at g'' , in conjunction with the lug f^3 of the lever, forms the third locking feature of importance in preventing the lock from being separated or 35 pried apart by any endeavor to separate the sashes. The socket g^3 is the catch proper to receive the bolt c , and when the latter has been locked in the former the window-sashes 40 are securely locked against any attempt to raise the lower sash.

The sash-lock thus constructed I apply to the two sashes X X', as follows: As shown in Figs. 1, 2, 8, I secure to the outer sash, X', 45 the catch G, so that it partially projects beyond the dividing-line of the sashes. Thus, let $x x$ represent the line dividing both sashes. I secure the catch G so that its bevel-face catch g and shoulder g'' project to the inside or over 50 a portion of the inside sash, X; hence, as the said projecting parts of the catch G would interfere with the raising and lowering of the inside sash, the latter is mortised, or has that portion thereof cut away, as indicated by the 55 letters x' . (See Figs. 8, 10.) Both portions of the sash-lock having thus been secured, respectively, to the meeting-rails of the sashes, (see Figs. 1, 2, 8,) the complete operation of the sash-lock is as follows: By referring to 60 Figs. 1, 3, 5, 7, 8, the sash-lock is represented in full-locked condition, preventing the sashes from being operated. It will be noted that the thumb-lever has its arm f'' in engagement with the mortise g' of the catch G under its 65 bevel-face at same time the lug f^3 of the thumb-lever is behind the shoulder g'' of the catch. Said locking features prevent the pry-

ing apart of the sashes, and render the sash-lock burglar-proof. At the same time the strong bolt c is locked in the socket of the 70 catch G, which prevents any forcible raising of the inside sash. To open the sash-lock the thumb-lever F is turned fully to one side, (see Fig. 2,) which disengages its arm f'' from the bevel-face catch g , also releases its lug f^3 from the shoulder of the catch G, hence unlocking 75 all the locking devices that exist top of the casing. At the same time the lever is so turned to one side that it actuates the spindle by its two arms, D D', to withdraw the bolt c 80 out of the catch G, and the sash-lock being in the unlocked position shown in Figs. 2, 4, the sashes can be freely raised or lowered. As soon as the thumb-lever is released, the spring 85 automatically restores the bolt and its connected parts to original position. I lay stress upon the self-closing of my sash-lock, which is accomplished as follows: In lowering or closing fully the inside sash, the lever, by its arm f'' , strikes against the incline face g , causing the lever to turn to one side sufficiently to prepare the bolt c (when it strikes against the shoulder g'') to complete the full movement on the 90 part of the lever; to clear the incline face and the spindle-connections, and to withdraw itself clear of the catch G. This done, the spring locks the bolt, and restores all parts to locked condition. The lever must be turned to one side to open the sash-lock, and this can only be done from the inside; but in fully closing the 95 inner sash, the sash-lock automatically closes or locks itself.

What I claim is—

1. The improved sash-lock, consisting, essentially, of the casing A, having spindle b, the arm-connections D D' to bolt c, forming part of which is the bearing-plate c', having slot c^2 , the spring E, the catch G, having socket g^3 , to operate as and for the purposes set forth. 105

2. The improved sash-lock consisting of the casing A, having spindle b, the arm connections D D', the bolt c, its bearing-plate c', having slot c^2 , the spring E, the thumb-lever F, having arm f'' , the catch G, having socket g^3 , 115 mortise at g' , and bevel-face at g , by means whereof both the bolt and the thumb-lever can be secured in the manner and for the purposes set forth. 110

3. In a sash-lock, the combination with a pivoted thumb-lever, F, having the arms f'/f'' , the latter provided with lug f^3 , the catch G, having mortise g' and shoulder at g'' , by means whereof the said lateral arm f'' , engaging the mortise of the catch at same time, brings in 120 engagement the lug f^3 with the shoulder on the catch, substantially as and for the purposes set forth. 125

In testimony of said invention I have hereunto set my hand.

GEORGE W. CURRY.
